MEANS FOR MIXING AIR AND GAS

Sam P. Jones, Dallas, Tex., assignor of forty per cent to E. W. Schadek, Dallas, Tex.

Application June 27, 1935, Serial No. 28,676

1 Claim. (CL 48—180)

This invention relates to new and useful improvements in means for mixing air and gas.

One object of the invention is to provide an improved gas mixer for gas engines, which is operated by the suction of the engine, whereby the gas and air is correctly proportioned and controlled by the suction of the engine to maintain highest efficiency under all conditions.

An important object of the invention is to provide an improved air and gas mixer for engines having a movable piston which is actuated by the suction of the engine for controlling the inlet of air and gas and also having a spring for returning the piston to its cut-off position, the mixer including a pressure actuated member which is connected with the piston and exposed to the suction of the engine, whereby an increased exposed area for moving the piston against the spring tension is had, which permits the piston to be moved by a lower suction which detracts less from the H. P. of the engine; the increased exposed area also allowing a stronger return spring to be employed which assures positive return of the piston to its cut-off position.

Another object of the invention is to provide a gas mixer for gas engines having a movable piston exposed to the suction of the engine for controlling the flow of gas and air therethrough and including a pressure actuated member which is exposed to the suction of the engine through restricted passages whereby fluttering of the piston in operation is prevented.

Another object of the invention is to provide an improved gas mixer, wherein a movable piston is employed for controlling the flow of gas and air into the engine, said mixer having means for increasing the richness of the mixture when the engine is accelerated or an increased load imposed thereon and decreasing the richness of said mixture when the load on the engine decreases or when the engine is slowed down, whereby the mixer may be applied to an engine operating under widely variable loads.

Still another object of the invention is to provide an improved gas mixer having a movable piston actuated by the suction of the engine for proportioning the air and gas entering the engine, which is so constructed that air at atmospheric pressure may be introduced behind the piston to aid the suction in operating said piston, whereby less suction is required to operate the piston which makes for increased efficiency in the operation of the engine.

A further object of the invention is to provide an improved gas mixer including a piston

which is rotatably mounted to control the flow of gas and air through the mixer and having means for easily and quickly rotating the piston to adjust the flow and then locking the same positively in its adjusted position, the adjusting means being simple in construction and arranged to be operated by one hand.

A still further object of the invention is to provide a diaphragm which is connected with the movable piston of a gas mixture and which is exposed to the suction of the engine, whereby the diaphragm will aid in operating the piston which allows operation of the piston with less suction, the diaphragm being connected to the mixer by removable retaining rings held in place by a resilient ring so that assembling and dismantling of the entire mixer is simplified for purposes of cleaning or for any other reason.

Another object of the invention is to provide an improved method of mixing air and gas for use in gas engines which includes introducing gas into a chamber and then introducing air circumferentially into said chamber around the gas, whereby a correct proportion of gas and air to make a proper mixture for normal operation of the engine is had, and automatically varying the proportion of gas and air to provide a richer mixture when the engine is accelerated or an increased load is imposed thereon, and automatically varying the proportion of gas and air when the engine is slowed down or the load thereon decreased.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a side elevation of a gas mixer, constructed in accordance with the invention, 40

Figure 2 is a plan view of the same,

Figure 3 is a transverse, vertical sectional view, taken on the line 3—3 of Figure 2, 45

Figure 4 is a transverse, vertical sectional view, taken on the line 4—4 of Figure 2,

Figure 5 is a horizontal, cross-sectional view, taken on the line 5—5 of Figure 1,

Figure 6 is a horizontal, cross-sectional view, taken on the line 6—6 of Figure 1, 50

Figure 7 is a horizontal, cross-sectional view, taken on the line 7—7 of Figure 1,

Figure 8 is a horizontal, cross-sectional view, taken on the line 8—8 of Figure 1, 55

Figure 9 is an enlarged transverse sectional view showing the connection between the piston and diaphragm.

Figure 10 is an enlarged sectional detail showing the operating lever for the retaining rings, and

Figure 11 is an enlarged plan view of said operating lever.

In the drawings, the numeral 10 designates 10 the housing of a gas mixer, which has a general cylindrical shape and which may be cast of one piece of metal, or other suitable material. The usual attaching flange 11 is provided at the upper end of the housing, and a cylindrical bore 12 extends axially therethrough.

In the upper or neck portion of the housing a butterfly valve 13 is mounted to swing on a diametrically extending shaft 14 which is journaled in the side wall of the housing. One end 20 of the shaft extends through the wall and has a throttle lever 15 secured thereto. The lever has a stop 16 and a set screw 17 for engaging a stud 18 on the housing, whereby the swinging of the butterfly valve is limited, as is the usual practice in the art.

The bottom of the housing is open and an external annular flange 19 extends around this open end. The upper end of said flange is beveled as clearly shown in Figure 10. A circular diaphragm case 20 is provided with an annular flange 21 at its upper end which is of the same diameter as the flange 19 and which is arranged to fit thereagainst. The top of the case is reduced whereby an annular shoulder 22 is formed and this reduced portion snugly engages in the open bottom of the housing with the shoulder 22 in engagement with the lower end of the bore 12 to close the lower end of said bore.

With the top of the case closing the bore, it 40 will be seen that the upper end of the flange 21 of the case snugly engages the underside of the flange 19. For securing the case to the housing, a split retaining ring 23 comprising sections A and B is provided. As shown in Figure 10, the 45 inner contour of said ring is such that a lower annular flange 24 engages under the flange 21 of the case while an upper flange 25 having a complementary bevel engages over the bevel flange 19 of the housing. The outer surface of the ring is formed with an annular groove 26 which receives a circular spring 27. The spring exerts its tension to force and hold the sections of the ring into close engagement with the flanges 19 and 21 to hold the case and housing 50 together. As shown in Figures 7 and 11, the ends of the sections A and B do not meet at one side of the housing but are cut off to form a space 28. Within this space, an operating lever 29 is located.

The lever is pivoted on a stud 29' which is 60 journaled in the diaphragm case (Figure 10) and it is obvious that the sides of said lever engage the ends of the sections A and B. When the lever is in the position shown in full lines 65 in Figure 11, the spring 27 holds the sections A and B in tight frictional engagement with the flanges 19 and 21, whereby the case is rigidly secured to the housing and is incapable of rotating with the relation thereto. However, when the lever is swung to the position shown in dotted lines, (Figure 11) it will be seen that it spreads the sections A and B of the ring 23 to move the same away from the outer periphery of both the flanges 19 and 21, under tension of the spring 27. This spreading is comparatively slight and

does not disengage the flanges 24 and 25 of the ring from the flanges 19 and 21, but merely breaks the tight frictional engagement between the ring 23 and flanges, whereby rotation of the diaphragm case 20 with relation to the housing 10 may be accomplished, as will be hereinafter explained.

A piston, or piston valve 30 is mounted to slide vertically within the bore 12 of the housing. The piston has an axial stem 31 which extends downwardly through the upper end of the diaphragm case 20 and is secured to the center of a suitable diaphragm 32 by a nut 32'. A sleeve 31' surrounds the stem 31 between the diaphragm and piston and this sleeve serves to space the parts 15 from each other. The lower end of the stem is formed with an integral extension 33 which depends therefrom, through the bottom of the diaphragm case. The lower end of the extension is threaded to receive a wing nut 34 and a coiled spring 35 surrounds the extension being confined between the bottom of the case and said nut. The spring constantly exerts its tension to hold the piston and diaphragm in a lowered position. It is pointed out that the suction of the engine 20 to which the mixer is attached acts upon the piston to raise the same.

In order to utilize this suction so that it may also act upon the area of the diaphragm to provide an increased lift area, communication is established between the diaphragm case above the diaphragm 32 and the area above the piston. To establish such communication, the bottom of the piston is provided with a plurality of ports 36 which encircle the stem 31. These ports communicate with an annular, vertical passage 37 which is formed between the sleeve 31' and an enlarged sleeve 38 which is slidably mounted in an opening 39 in the top of the diaphragm case 20. The enlarged sleeve is of substantially the same length as the sleeve 31' but it is noted that said sleeve 38 is not secured to either the bottom of the piston or the top of the diaphragm although it is confined therebetween. The lower end of the sleeve 38 is provided with openings 40 which communicate with the space above the diaphragm, and thus, it will be seen that the engine suction above the piston will act upon the diaphragm through the ports 36, passage 37 and openings 40. Thus, since the suction still 50 acts upon the cross-sectional area of the piston, the provision of the diaphragm provides an increased area for the suction to act upon in lifting the piston. With such increased area, less suction is required, and since the suction necessary to operate the mixer, detracts from the H. P. of the engine, it is obvious that the less suction that is necessary, makes for the more efficient operation of the engine.

It is pointed out that the ports, passages and 60 openings through which the suction acts upon the diaphragm forms a restricted passage whereby the suction must act gradually upon the diaphragm. Therefore, fluttering of the piston during lifting of the piston is eliminated as the 65 same moves up gradually. If desired, a flanged washer 30', having openings in its upper end may be located over the ports 36. Brass, wool, or similar substance is confined within the washer to prevent a backfire of the engine from igniting an explosive mixture, if such mixture was present in the diaphragm case. This washer, however, is not essential.

The piston 30 is provided with a rectangular gas port 41 (Figures 3 and 6) at its lower end. 75

Above the gas port the piston has an annular air opening or slot 42 which is continuous except for narrow webs 43 which are cut back from the piston surface, so as not to contact the bore 12. 5 A nipple 44 is preferably made integral with the housing near its lower end and is threaded to receive a gas inlet pipe 45. At the inner end of the nipple a rectangular gas inlet port 46 is formed. An annular continuous air inlet slot 47 extends 10 through the wall of the housing 10 above the nipple and this slot is enclosed by a circular flared hood 48 which is made integral with the outside air inlet 49. (Figure 5.)

The gas ports 41 and 46 in the piston and housing at the inner end of the nipple are of equal height and the air slots 42 and 47 are also of equal width. The air openings and gas openings are spaced equally from each other in both the piston and housing, consequently both are opened 20 in proportion to each other. In other words, when the air slot 42 begins to register with the air inlet slot 47, the gas ports 41 and 46 come into registration.

The interior of the piston 30 has a vertical 25 riser pipe 50 which extends through the bottom of the piston and has its upper end terminating adjacent the air inlet slot 42. Thus, air may pass downwardly through said pipe and enter the space 51 between the underside of the piston and the top of the diaphragm case 20. The upper 30 end of the pipe is internally threaded to receive a removable plug 52. A radial port 53 is formed in the housing 10 at the lower end thereof and this port establishes communication between the atmosphere and the space 51 below the piston. This port is internally threaded and is preferably 35 of the same diameter as the pipe 50, whereby the plug 52 may be interchanged between the port and pipe. As will be explained, either one or the other is plugged.

When the engine, to which the mixer is attached, is stopped, the spring 35 which is under tension (Figures 1, 3 and 4), will pull the piston downwardly to its closed position, whereby the gas ports 47 and 46 and the air slots 42 and 41 45 are out of registration. In order to effectually close the gas port 46, and prevent gas leakage, the piston 30 is given a loose sliding fit in the bore 12, so that it may undergo a limited lateral movement therein. A wedge key 54 is made integral with the top of the diaphragm case 20 extending upwardly therefrom. This key engages 50 a complementary inclined slot 55 (Figure 3) formed in the piston. When the piston is pulled downwardly by the spring it is shifted laterally 55 by the key, which is located substantially diametrically opposite the gas inlet port 46. This forces the wall of the piston into intimate contact with the wall of the bore 12 surrounding the port 46, thereby sealing off said port. It is noted that when the piston is in its lowered position, it is resting on the wedge-shaped key, there being the space 51 between the piston and top of the case 20, whereby the lateral displacement of the piston is assured.

65 When the piston is laterally displaced as above described, the upper end of the stem 31 and sleeve 31' are also displaced. This causes a distortion of the flexible diaphragm but since the lateral movement is so slight, this distorting is practically negligible. The bottom of the piston will slide laterally on the upper end of the enlarged sleeve 38 and since it is slidably mounted in the opening 39 in the diaphragm case it will not interfere with this lateral movement.

75 When it is desirable to shift the gas ports 41

and 46 with relation to each other whereby the amount of gas flowing therethrough is changed, it is only necessary to rotate the diaphragm case 20 which will rotate the piston through the medium of the wedge key 54 in constant engagement with the slot 55 in the piston. To rotate the diaphragm case, the lever 29 is swung to loosen the frictional engagement of the sections A and B of the split retaining ring 23, as has been explained, after which the case may be easily rotated to 10 make the adjustment. It is pointed out the lever may be swung with the thumb while the case 20 is engaged by the fingers so that the adjustment may be made with one hand. As soon as the lever is released, the spring 27 will immediately 15 move the split ring 23 into tight frictional engagement.

The arrangement of the split retaining ring not only makes for easy adjustment and positive holding when in adjusted positions but also provides for easy dismantling of the device for cleaning, or other purposes. To dismantle the mixer, the spring 27 is rolled upwardly out of the groove 26 in the ring so as to encircle the lower end of the housing 10. The split ring 23 is then 20 removed and the diaphragm case 20 and piston may be removed. The entire operation is but a 25 matter of a few seconds. The assembling is just as simple.

Assuming that the engine to which the gas 30 mixer is applied is to be operated under an even load and at a substantially fixed speed, the plug 52 is inserted in the pipe 50 within the piston. This leaves the radial port 53 in the housing wall below the nipple 44 open, whereby air under atmospheric pressure may enter the space 51 below the piston 30.

The throttle valve 13 is opened and the engine started. The suction of the engine reduces the pressure above the piston and air at atmospheric pressure which has entered the space 51 below said piston through the opening 53, serves to raise the piston upwardly. Then suction will also act upon the upper face of the diaphragm 32 through the ports 36, passage 37 and opening 40. The increased area upon which the suction may act reduces the amount of suction necessary to raise the piston and therefore less power will be taken from the engine. As the piston raises, the gas ports 41 and 46 and air slots 42 and 47 move 45 into registration to admit the proper proportion 50 of gas and air to the engine (not shown).

It is obvious that since the gas enters at the bottom of the piston some of this gas will enter the diaphragm case above the diaphragm 32 through the passage 37 and ports 40 and this 55 space above the diaphragm forms a gas chamber 38'. This occurs when the mixer is inoperative or when the engine is slowed down, whereby this gas is stored in the gas chamber 38' above the diaphragm. Thus, when the engine is started 60 the diaphragm moves upwardly and forces this accumulated gas upwardly into the piston to make a richer mixture at starting and accelerating. Similarly, as the engine slows down, some 65 gas is drawn back into the diaphragm case by the downward movement of the piston, whereby the mixture is thinned as the engine idles down. As described above, with the plug 52 in the pipe 50, the mixer is applied to an engine which is operating under a substantially constant or uniform speed or load, whereby there is little change 70 in the position of the diaphragm when the engine is running.

However, when the mixer is employed with an engine operating under widely variable loads or 75

speed, the plug 52 is removed from the pipe 50 and screwed into the port 53 to close the same. Thus, when the engine is started and the piston and diaphragm begins their upward movement, 5 air from the inlet 49 enters the pipe 50 and flows into the space 51 below the piston. This air is under a pressure below atmospheric because it is subjected to the engine suction. Therefore the pressure of this air is equal to the pressure of the 10 air of the piston, whereby the piston is balanced. Thus, the suction acting upon the diaphragm causes the same to move upwardly raising the piston. Therefore, with the plug 52 in the opening 53, the diaphragm does all the lifting. Since 15 the engine is operating under variable loads, acceleration thereof must be had. Each time, the engine is accelerated, the piston and diaphragm move upwardly, whereby the diaphragm forces additional gas which has been stored above the 20 diaphragm into the piston to make a richer mixture at the time of acceleration. This gives the engine a more rapid pickup. As the engine slows down or the load thereon decreases the diaphragm and piston move downwardly. This permits gas 25 to flow back into the case 20 and at the same time forces the air in the space 51 upwardly through the pipe 50 into the piston. The introduction of this air together with the release of gas into the diaphragm case makes for a lean 30 mixture as the engine idles down, which is exactly the time when such mixture is desirable. Thus, it is seen that maximum efficiency of the engine is had under all conditions. The interchangeability of the plug 52 between the pipe 50 and 35 port 53 may be accomplished quickly and easily, whereby the device may be applied to an engine operating under any condition.

It is again pointed out that the provision of the retaining ring not only permits a quick and easy adjustment of the case 20 with relation to the housing, but further forms a rigid connection between the housing and case. Also, assembling 5 and dismantling of the entire device can be readily accomplished without removing the housing from the engine to which it may be fastened.

What I claim and desire to secure by Letters Patent is:

A gas mixer including, a housing having gas and air inlets, a piston slidable in said housing arranged to be operated by the suction of an engine and having gas and air inlets located to register with the inlets of the housing when the piston is slid, a diaphragm case communicating with the interior of the piston to permit gas to flow from the piston to the chamber, a retaining ring engaging the case and housing for securing the case to the housing, resilient means for holding the retaining ring in frictional engagement with the case and housing to prevent rotation of the former with relation to the latter, means for loosening said retaining ring for permitting such rotation, and a diaphragm within the case connected to the piston and exposed to the suction of the engine through a restricted passage whereby an increased area is exposed to the suction to effect actuation of the piston with less suction, the connection between the piston and diaphragm causing the latter to be actuated with the piston, whereby said diaphragm forces the gas in the case into the piston to increase the richness of the mixture.

SAM P. JONES.
